J. NUTRY.

CONTACT REEL AND BRUSH.

1,242,716.

Patented Oct. 9, 1917.

UNITED STATES PATENT OFFICE.

JOHN NUTRY, OF BROOKLYN, NEW YORK.

CONTACT REEL AND BRUSH.

1,242,716.

Specification of Letters Patent.

Patented Oct. 9, 1917.

Application filed August 7, 1916. Serial No. 113,515.

To all whom it may concern:

Be it known that I, JOHN NUTRY, residing at Brooklyn, in the county of Kings and State of New York, have invented certain new and useful Improvements in Contact Reels and Brushes, of which the following is a specification:

This invention relates to a contact reel and brush. It is particularly adapted for use in connection with automatic telegraphing instruments and the like, although it is not necessarily limited to use in connection with such instruments.

The object of the invention is to provide an improved, simple, durable and uniformly efficient device of this character.

Further object is to provide a construction which will occupy a minimum of space, but which may nevertheless be made strong and substantial.

More detailed object is to provide a contact reel which is made up of two or more annular members fixed to each other in concentric relation, so that one of said members will constitute an insulating element for maintaining the brush out of contact with portions of another of said elements except at the desired times, also to provide a supporting member for the contact reel which will coöperate with portions of said reel to positively guide the movement thereof and at the same time serve to maintain the contact elements of the reel in efficient operative condition.

A further object is to provide an improved form of brush for coöoperating with the improved reel, also to so form the brush as to coöperate with an unusually strong and reliable brush-guiding member.

Further object is to provide an improved form of pawl for coöoperating with the improved form of reel.

Other objects and aims of the invention, more or less specific than those referred to above, will be in part obvious, and in part pointed out, in course of the following description of the elements, combinations, arrangement of parts and applications of principles, constituting the invention: and the scope of protection contemplated will be indicated in the appended claims.

In the accompanying drawings which are to be taken as a part of this specification and in which I have shown merely a pre-

ferred form of embodiment of the invention:

Figure 1 is a side elevational view of a contact reel and brush, the supporting member and the stop pawl being illustrated in their normal positions, and adjacent parts of an automatic telegraphing machine being shown in transpose section.

Fig. 2 is a perspective view of the supporting member of "carriage" for the contact reel.

Fig. 3 is an enlarged vertical sectional view taken substantially upon the plane of line III—III of Fig. 1, like in the direction of the arrow.

Fig. 4 is a perspective view of the contact brush, illustrating the guiding means therefor and

Fig. 5 is a perspective view of the stop pawl.

Referring to the drawings for a detailed description of the structure which is illustrated therein the reference character L indicates the contact reel. The reference character G indicates the contact brush. The reference character H indicates the supporting member or "carriage" for the contact reel, and the reference character A indicates the stop pawl.

The contact reel L is made up of three annular members fixed flat against each other as clearly indicated in Fig. 3. The central member 1 is a ring of insulating material. The side members 2 are made of metal or other conducting material. The central member 1 is of slightly greater diameter than the members 2 so that it presents a smooth annular surface projecting beyond the outer edge of the members 2.

The inner annular edge of at least one of the members 2 is provided with gear teeth arranged, when the reel is moved downwardly to engage the teeth of the rotating drive roller 4.

The members 2 may be fixed to the member 1 in any suitable manner but are preferably connected by small rivets 5 or the like.

When the reel is lowered into engagement with the roller 4 the engagement of the teeth 3 with the teeth of the roller will cause the reel to rotate in the manner well-known in the art.

The brush G is preferably made from

sheet metal bent into U-cross-section. At one end it is enlarged and provided with a slot 6 pivotally engaging over a supporting shaft or wire 7, the slot 6 being directed 5 downwardly so that the weight of the brush, together with the tension of a light spring 8, will suffice to maintain the brush against accidental displacement. The U-shape of the brush provides 2 slots 6 for each 10 brush disposed to engage the wire 7 at points spaced apart so that tendency of the brush to tilt to one side or the other is counteracted.

Intermediate its length the upper wall 10 15 of the brush is cut away, to provide a free passageway between the legs thereof for a guide member 15 as clearly illustrated in Fig. 4. This guide member is rigid and serves to positively retain the outer end of 20 the brush against displacement but leaves it free to move in a vertical direction.

A small section 16 of the upper wall is left uncut so as to constitute attaching- 25 means for the upper end of the spring 8. The portion 16 is preferably indented as clearly seen in Fig. 4 to provide a better seat for engagement by the upper end of the spring.

At the outer end of the brush a depend- 30 ing arm 9 is provided for engaging the contact reel. This arm is formed by bending down an extension of the upper or connecting wall 10. The arm 9 is slotted so as to provide a pair of spaced fingers 11 at its 35 lower end. The slot is disposed so as to straddle the insulating member 1 of the reel and the depth of the slot is such that when the lower end surfaces 12 of the fingers 11 are raised upon the outer annular surface 40 of the members 2 of the reel the surface 13 between the fingers is spaced slightly away from the upper edge surface of the member 1. The members 2 however have portions cut out therefrom as at 14 so that the outer 45 annular surface is broken. Normally the arm 9 stands at the point of one of the cut-away portions 14 so that the surface 13 between the fingers rests upon the edge of the insulating member 1 and the lower ends of 50 the fingers depend slightly below the circular plane of the outer annular edges of the members 2.

When the reel is rotated the successive corners 15 engage against the lower sur- 55 faces 12 of the fingers and lift the same upwardly. This provides a good clean rubbing contact between the fingers and the projecting portions of the members 2.

The surfaces 12, as well as the corners 15, 60 are preferably slightly beveled to facilitate the lifting action.

As the reel moves downwardly into engagement with the roller 4 it is followed closely by the arm 9. So long as the fingers 65 depend into one of the cut-out spaces 14

there is no electrical engagement between the brush and the members 2 of the reel. The electrical connection is made from the roller 4, through the members 2 to the brush only when the reel is rotated and the projecting portions of the members 2 engage the fingers. 70

The projecting portions of the members 2 accordingly are given definite proportions relatively to each other so as to define dots and dashes. A series of projecting portions thus constitute one letter, as will be readily understood. At the end of each series of projecting portions a laterally extending pin 14 is arranged to engage the stop pawl A so that when the letter has been impressed upon the line the stop pawl will be moved by one of the pins 14 and the reel will be caused to return upwardly to its normal position out of contact with the roller 4. This action 80 is accomplished by mechanism not shown and not forming a part of this invention but well known in the art. 85

There may be as many series of project- 90 ing portions as may be accommodated in the circumference of the reel.

The stop pawl is clearly illustrated in Fig. 5 where it is seen also to be of U-cross-section so as to provide a pair of depend- 95 ing shoulders 17. The U-shape of the pawl permits the same to straddle all three mem- bers of the reel and to dispose the shoulders 17 in position to be engaged by the pins 14.

The carrier H comprises a body-part of metal formed with a semi-circular portion 18, a forward extension 19, and a rearward extension 20. The forward extension is in- 100 tended to be operated upon by the character keys to cause said end to be depressed. The rearward extension is provided with an up- 105 wardly opening slot 21 for pivotally en- gaging a rod or wire 22. The semi-circular portion is adapted to accommodate and partly encircle the reel and for this purpose it is formed with an inner curved surface 23 of approximately the same curvature as the edge of the member 1 of the reel. Curved strips or plates 24 of insulating material are fixed by rivets or the like 25 to the oppo- 110 site side surfaces of the semi-circular por- tion for co-operating with the surface 23 to provide a curved pocket or runway into which the projecting portion of the member 1 of the reel is rotatably received. 115

The pocket or runway is slightly larger 120 in cross-section than the projecting portion of the member 1 of the reel, as seen at the bottom of Fig. 3, so as to permit of a free and easy rotary movement of the reel there- 125 in. Also the outer surfaces of the extensions 26 as formed upon the members 2 of the reel are permitted to bear against the surfaces of the plates 24 so that the frictional rubbing engagement between said extensions and the insulating material of the plates will cause 130

the outer surfaces of the extensions to be maintained bright and clean at all times during the operation of the device. Good electrical contact between said extensions of the 5 brush will therefore be assured.

The carrier is maintained in its normally elevated position by means of a spring 27 which engages between the carrier and the support 28 of the guides 15.

10 The lower end of the spring is preferably connected to the carrier so that the tension of said spring will not be materially altered during the operation of the device. The connection is conveniently made by providing 15 a pin 29 to bridge the space between the plates 24 at the rear end of said plates where the plates project slightly above the body of the carrier. The spring engages the bridging portion of the pin and forms 20 an ideal attachment.

It will be noted that those portions of the brush G which are intended to engage the contact extensions of the reel have no rubbing contact whatever except with the contact 25 extensions. The likelihood of an accumulation of any kind upon the contact portion of the brush due to rubbing over a solid insulating section is therefore avoided.

It will also be noted that the fingers 11, 30 straddling the projecting portion of the reel, serve to guide and maintain the brush against accidental displacement. The projecting annular portion of the member 1 of the reel constitutes a guide element for the 35 brush, and acts with the fingers 11 and the surface 13 to positively hold the brush at all times in proper and accurate coöperative relation with the contact extensions of the members 2.

40 It will also be noted that if desired the outer surface of the insulating member 1 of the reel may rest in rubbing contact with the surface 23 of the carrier.

As many changes can be made in this construction without departing from the scope 45 of the following claims, it is intended that all matter contained in the above description, or shown in the accompanying drawings, shall be interpreted as illustrative only 50 and not in a limiting sense.

Having thus described my invention what I claim as new and desire to secure by Letters Patent is:

1. A contact reel and brush, the contact 55 reel comprising a ring of insulating material and a series of contact elements carried thereby defining a complete circle and spaced inwardly from the periphery thereof, and the brush comprising a slotted part for 60 straddling the projecting portion of the ring and for engaging said contact elements.

2. A contact reel and brush, the contact 65 reel comprising a member formed with a plurality of contact elements arranged in a complete circle, an annular member of in-

sulating material projecting beyond said contact elements to constitute a guide with respect thereto, the brush comprising a finger for engaging said contact elements and comprising a surface portion for engaging the annular edge of said insulating material, whereby to guide the finger in proper coöperative relation with said contact elements. 70

3. A contact reel and brush, the contact reel comprising a ring of insulating material and two rings of conducting material, the ring of insulating material being of greater diameter than the rings of conducting material so as to provide an annular portion of insulating material projecting beyond the circumferential edges of the rings of conducting material, the circumferential edges of the rings of conducting material having portions cut out therefrom to leave contact 75 elements, and the brush comprising an arm formed with a pair of fingers disposed to straddle the projecting portion of the ring of insulating material so that the ends of said fingers are guided in coöperative position relatively to said contact elements. 80

4. A contact reel made up of an annular member of insulating material and an annular member of conducting material each defining a complete circle, the annular member of insulating material being of greater diameter than the annular member of conducting material so as to provide an annular portion of insulating material projecting beyond the outer circumferential surfaces of 100 the annular member of conducting material to serve as brush-guiding means, and the outer circumferential surface of the member of conducting material having portions cut therefrom whereby to provide contact elements adjacent the brush-guiding means. 105

5. A contact reel made up of an annular member of insulating material and an annular member of conducting material each defining a complete circle, the annular member of insulating material being of greater diameter than the annular member of conducting material so as to provide an annular portion of insulating material projecting beyond the outer circumferential surfaces of 110 the annular member of conducting material for coöperating with the annular member of conducting material having contact portions disposed adjacent the projecting portion of the annular member of insulating material, 115 and the projecting portion of the annular member of insulating material comprising a guide means to maintain the reel in a suitable carrier. 120

6. A contact reel comprising an annular insulating member and a contact member, said annular insulating member having a portion disposed to constitute a guide for rotatably supporting the reel in a suitable carrier. 125 130

7. A contact reel and carrier therefor, the contact reel comprising a series of contact elements arranged in a complete circle and an annular member of insulating material 5 upon which said contact elements are supported, the annular member of insulating material having an annular portion projecting beyond said contact elements to form a guide for engaging the carrier, and the carrier having a portion for engaging said guide to rotatably support the reel.

8. A contact reel and carrier therefor, the contact reel comprising a series of contact elements arranged in a complete circle and 15 an annular member of insulating material upon which said contact elements are supported, the annular member of insulating material having an annular portion projecting beyond said contact elements to form a 20 guide for engaging the carrier, and the carrier having a portion for engaging said guide to rotatably support the reel, and having another portion to be engaged by said contact elements as the reel rotates whereby 25 to maintain the contact elements clean.

9. A contact reel and carrier therefor, the contact reel comprising a series of contact elements in circular alinement and having unobstructed spaces therebetween, and the 30 carrier comprising means forming a circular pathway along which said contact elements rub.

10. A contact reel and carrier therefor, the contact reel comprising a series of contact elements in circular alinement and have 35 unobstructed spaces therebetween, and the carrier comprising means forming a circular pathway engaging the contact elements to support the reel.

40 11. A brush of the type disclosed comprising a member formed of sheet metal bent into U-shape in cross-section, the legs of the U at one end of the brush being slotted for engaging a support at spaced points upon 45 the support, and the connecting portion of the U being extended at the opposite end of the brush beyond the adjacent ends of the legs of the U and bent downwardly across the ends of said legs to constitute a contact 50 arm.

12. A brush of the type disclosed comprising a member formed of sheet metal bent

into U-shape in cross-section, the legs of the U at one end of the brush being slotted for engaging a support at spaced points upon 55 the support, the connecting portion of the U being extended at the opposite end of the brush beyond the adjacent ends of the legs of the U and bent downwardly across the ends of said legs to constitute a contact arm, 60 the connecting portion of the U being cut away intermediate the length of the brush to provide an unobstructed passageway vertically between the legs of the U for a suitable guide member.

13. A brush of the type disclosed comprising a member formed of sheet metal bent into U-shape in cross-section, the legs of the U at one end of the brush being slotted for engaging a support at spaced points upon 70 the support, the connecting portion of the U being extended at the opposite end of the brush beyond the adjacent ends of the legs of the U and bent downwardly across the ends of said legs to constitute a contact arm, 75 and the connecting portion of the U being cut away at spaced points intermediate the length of the brush to provide a narrow bridge at one point between said legs for the attachment of a controlling spring.

80 14. A stop pawl made of sheet metal bent into U cross-section to provide a pair of depending legs at one end for straddling a contact reel or the like so that the ends of the legs will engage operating pins carried at 85 the sides of the contact reel, and for providing spaced pivot forming portions at the opposite end.

90 15. A contact reel and brush, the contact reel comprising an annular guide ring defining a complete unbroken circle and a contact element, the brush comprising a part at all times engaging the annular unbroken portion of the guide ring so as to be positively guided thereby retaining another part of the 95 brush in position to coöperate with said contact element.

In testimony whereof, I affix my signature in the presence of two witnesses.

JOHN NUTRY.
